UNITED STATES PATENT OFFICE.

ERASTUS E. WINKLEY, OF LYNN, MASSACHUSETTS, ASSIGNOR TO UNITED SHOE MACHINERY CORPORATION, OF PATERSON, NEW JERSEY, A CORPORATION OF NEW JERSEY.

FEEDING MECHANISM.

1,368,313.

Specification of Letters Patent.

Patented Feb. 15, 1921.

Original application filed May 18, 1916, Serial No. 98,283. Divided and this application filed March 18, 1918. Serial No. 223,220.

To all whom it may concern:

Be it known that I, ERASTUS E. WINKLEY, a citizen of the United States, residing at Lynn, in the county of Essex and State of Massachusetts, have invented certain new and useful Improvements in Feeding Mechanisms; and I do hereby declare the following to be a full, clear, and exact description of the invention, such as will enable others skilled in the art to which it appertains to make and use the same.

This invention relates to mechanisms for automatically feeding heel-lifts or other pieces of shoe stock, and it is applicable particularly to machines for sorting or grading such pieces in accordance with their mass, thickness or other characteristics, although, broadly considered, the invention is adapted for general utility in feeding pieces of various kinds and for many different purposes.

The present invention is an improvement on the machine for feeding and sorting or grading pieces of shoe stock illustrated and described in Letters Patent of the United States No. 1,270,476, granted June 25, 1918, to the present applicant.

One object of the invention, relating particularly to machines for handling heel-stock, is to provide machines of that type with improved means for holding a stack of pieces of stock and feeding or delivering them to the other instrumentalities of the machine. To that end, the feed-mechanism of the present invention includes, in addition to elements employed in the machine disclosed in the above-mentioned application, an adjustable gage-member adapted to coöperate with the breast-edges or surfaces of the pieces of stock, so as to insure proper alignment of these pieces at the time of delivery from the stack. With respect to the feeding means, the invention also embraces improved stop-fingers for engaging the end-most pieces of the stack and these stop-fingers are rotatably mounted on an inclined pivot so that their path of movement is at a slight angle to the face of the end-most piece in the stack whereby engagement with the edges thereof is avoided.

Another object of the invention is to provide a machine of the class in question with a picker-mechanism of simple and efficient

form. The present inventor has devised a means of handling or feeding pieces of leather, or other shoestock, by which pieces of stock are engaged, withdrawn from a supply, and then transferred to another point and released, by "pickers," or devices provided with claws which engage and penetrate the substance of the stock so as to hold the piece of stock securely during the transferral, and to discharge it in a position having a definite relation to that in which it is first engaged. The picker-mechanism of the present invention performs this function, and the improvements in question relate particularly to the manner in which the claws are arranged and operated, and to the multiple arrangement of the pickers and means for positively locking the picker mechanism in its operative positions.

To the end last mentioned, each picker of the present invention is provided with one or more claws which project helically from a shank or head, and are so actuated that they may be caused to enter the substance of a piece of stock by a combined rotary and advancing movement in extension of their curvature. Other improvements in the picker-mechanism and the parts associated therewith reside in the means for securing the claws removably in place, the mechanism by which the advancing, retreating and rotary movements are imparted to the pickers, the means for holding the piece of stock against rotation during the rotary disengaging movement of the picker, and the means for positively locking the rotatable multi-picker device in its operative positions.

Other objects of the invention, and the features of construction and operation by which they are attained, will be set forth hereinafter, in connection with the description of the illustrated embodiment of the invention.

In the accompanying drawings, Figure 1 is a side-elevation of a machine embodying the present invention; Fig. 2 is a vertical section on the line 2—2 in Fig. 1; Fig. 3 is a plan-view of a portion of the machine; Fig. 4 is a vertical section on the line 4—4 in Fig. 1, but on a larger scale than the latter figure; Fig. 5 is a section on the line 5—5 in Fig. 1, but on a larger scale; Fig. 6 is a

2

section on the line 6—6 in Fig. 1, but on a larger scale; Fig. 7 is a detail plan-view, partly in section on the line 7—7 in Fig. 6; Fig. 8 is a side-elevation, partly in vertical section on the line 8—8 in Fig. 3, showing particularly the picker-mechanism of the machine; Fig. 9 is a horizontal section on the line 9—9 in Fig. 8, but on a larger scale than the latter figure; Fig. 10 is an elevation looking from left to right in Fig. 9; and Fig. 11 is a section on the line 11—11 in Fig. 8, but on a larger scale than the latter figure.

The invention is illustrated as embodied in a machine of the type disclosed in the above mentioned Letters Patent and also in Letters Patent No. 1,280,349, granted October 1, 1918, to the present applicant and of which this application is a division. In machines of this type, the stock which is handled consists of pieces of leather or other sheet-material which have been die-cut in the form of lifts suitable for use in the manufacture of shoe-heels. The operation performed upon these heel lifts, by the machine in question, is that of grading or sorting them in accordance with a mass-characteristic of the lifts. This operation is performed by operative instrumentalities which are adapted to subject each heel-lift to a heavy pressure over a definite limited portion of its area, and thereafter to discharge the lift into one or another of a series of stack-holders in accordance with the thickness of the lift at said definite portion when subject to the said compression.

While the various features of the present invention are useful, and may be conveniently described as employed, in connection with machines of the type and performing the specific operations just described, the invention is not limited to embodiment in such machines, but its various features are useful in connection with various machines for handling stock of different kinds and for performing various operations upon such stock. Accordingly, the machine will not be described herein in its entirety, but only so far as is necessary for an understanding of those parts which pertain to the feed-mechanism.

In the illustrated machine, the heel-lifts to be operated upon are held and advanced in a horizontally extending stack, upon a feed-table, and are withdrawn one at a time from the end of the stack by means of the picker-mechanism hereinafter described. Each lift so withdrawn is then deposited, by the picker-mechanism, in one of a circular series of receptacles provided at the periphery of a carrier which rotates about a vertical axis. The carrier rotates with a step-by-step movement, thus bringing each lift successively to a point at which it is operated upon by the pressing instrumentalities, and then to a series of points in

registration with a series of stack-holders, into one or another of which the lift is discharged.

In its general structure the machine comprises a hollow column 24, upon the upper end of which is fixed a generally-circular frame-plate 26, while a second stationary frame-plate 28, similar in form, is fixed above the plate 26 and connected rigidly thereto by uprights 30. Intermediate the stationary plates 26 and 28, and loosely mounted upon a central vertical sleeve 29, is an intermittently rotated carrier 31 having a plurality of peripheral lift-receiving receptacles 33. The feed mechanism is supported upon a feed-table in the form of a bracket 32, which extends from one side of the frame-structure just above described. The various mechanisms of the machine are actuated by cams mounted upon a cam-shaft 34 which is journaled, in horizontal position, within the lower part of the column 24, as shown in Fig. 2.

The feed-mechanism is shown particularly in Figs. 1, 3, 4, 5, 6, 7, and 8. The stack of lifts X is supported upon a grooved horizontal rail 36, which is mounted above the feed-table 32, and the lifts rest upon this rail with the curved back-portions of their edges downward. The stack of lifts is supported laterally by guides 37, which constitute parts of housings in which two endless chains 38 are arranged with parallel stretches extending alongside the stack. Each chain is provided, at intervals, with 100 spring-pressed pointed pawls 40, which extend inwardly beyond the guides 37 so that they may engage the lateral margins or the side edges of whatever lifts chance to lie adjacent to them, and thus drive the stack 105 forwardly as a consequence of the movement of the chains. Owing to the yieldable character of the pawls, additional lifts may be introduced between them by pushing the lifts forward between the chains and into engagement with the rearmost lift in the stack. Fig. 5 shows, at the left, a rear-view of one of the pawls, together with a sectional view of another pawl and the spring 42 by which it is actuated.

110 The chains 38 are supported by means of sprocket-wheels 46, the wheels being fixed on the upper ends of shafts 48 which are journaled vertically in two frames 44. In order to drive the chains, the shafts at the inner ends of the frames are provided, as shown in Fig. 4, with worm-wheels 50 at their lower ends, and these worm-wheels engage right and left hand worms on a shaft 52 which is journaled transversely on the feed-table 32. The shaft 52 is actuated intermittently, by means of a rocker-arm 54 pivoted on its outer end, this arm constituting a member of a roller-wedge clutch as shown in dotted lines in Fig. 1, the other 120

member of the clutch being a disk 55 fixed on the shaft.

The arm 54 is connected, by a link 56, with one arm of a bell-crank lever 58 pivoted on a bracket 59 depending from the feed-table. The other arm of the lever is forked and provided with rollers which engage an annular groove in a sleeve 64 which is mounted on a shaft 62. The shaft is supported, at one end, in a bearing on the bracket 59. The sleeve 64 is free to slide upon the shaft, but is pressed toward a collar 60, which is fixed on the shaft, by means of a spring 66 coiled about the shaft. The other end of the spring rests against a collar 68 which is fixed to the shaft.

By suitable means (not shown) intermittent longitudinal movements are imparted to the shaft 62, and at each left hand movement, the sleeve 64 rocks the lever 58 in a direction to cause the arm 54, acting through the friction-roller, to impart a partial rotation to the shaft 52. This motion is transmitted to the chains 38 in a direction to cause them to advance the stack of heel-lifts on the rail 36. The movement of the chains is continuous until the movement of the stack is arrested by means hereinafter described, and thereafter the continued movement of the shaft 62 merely causes compression of the spring 66. The opposite movement of the shaft 62 is imparted positively to the lever 58 by means of the collar 60, so as to rock the arm 54 back to its original position.

To adjust the feed-mechanism for lifts of different sizes, vertical movement of the rail 36 is necessary. Accordingly this rail is supported on two stems 70, which slide vertically through the feed-table (Figs. 1 and 4). Each stem is provided, at its lower end, with a pin 72 which is engaged by the slotted end of an arm 74, and these arms are fixed on a rock-shaft 76 extending lengthwise of the table. At the outer end of the rock-shaft, an arm 77 is fixed, and this arm is provided with a binding-screw 78, which extends through a slot in the flange at the end of the table and constitutes means by which the arm 77 and the rock-shaft may be rocked and then fixed in adjusted position, the rocking movement resulting in vertical movement of the stems 70 and the rail 36.

The adjustment of the feed-mechanism also requires movement of the guides 37 and the feed-chains toward and from each other. Accordingly the frames 44 are arranged to move transversely on the feed-table, being normally fixed to the table by binding-screws 80 which project through slots in the base-webs of the frames, as shown in dotted lines in Fig. 4. Sockets 82, at the ends of the frames 44, are engaged by levers 84, the hubs of which are loosely

mounted, in pairs, on two rods 86 fixed longitudinally beneath the feed-table. The levers 84 of each pair are connected together by gear-teeth 88, so as to have equal movements in opposite directions. By this arrangement the frames 44 are held always parallel and equidistant from the rail 36.

The feed-mechanism of the present machine is similar, in its general characteristics, to that disclosed in Letters Patent No. 1,280,349, and it is therefore not claimed broadly as a part of the present invention. It involves, however, an additional feature constituting an improvement over the mechanism of the said patent. At the inner end of the stack of lifts, means are provided, not only for supporting them below and laterally, but also for engaging the upper or breast edges of a plurality of the lifts to align them and prevent possible upward displacement thereof as their curved lateral edges are acted upon by clamping means described in said application and to insure the exact alignment and correct location of the lifts at the time when they are withdrawn from the feed-mechanism by the picker-mechanism. The means in question are shown as embodied in the form of a gage-plate 92 which is carried at the lower end of a stem 94 as shown particularly in Fig. 6. The stem 94 slides vertically in a guide-way 96, and is provided with a pin 98 which engages the forked end of a lever 100. The lever is connected, by a rod 102, with an arm 104, this arm being integral with the hub 106 (Fig. 4) of one of the levers 84. A gear-segment 107 on the hub 106 meshes with a segment 90 fixed on the shaft 76. From this arrangement, it results that the adjustment of the arm 77 causes, in addition to the adjustment of the other parts of the feed-mechanism, a corresponding adjustment of the position of the gage-plate 92, so that this plate is always in a position to engage the breast edges of the heel-lifts which the feed-mechanism is otherwise adjusted to handle.

The inner end of the stack of heel-lifts is normally supported by a pair of stop-fingers 108, shown particularly in Figs. 6 and 8. These fingers are pivoted on a stud 110, which is mounted in inclined position on the feed-table, and the fingers are provided with depending arms which are connected, by links 112, with a sleeve 114. This sleeve 120 slides upon a rod 116 which is fixed on the feed-table at a right angle to the stud 110. The sleeve 114 is connected, by links 118, with an arm 120 which projects from a sleeve 122, and the sleeve is journaled on a rod 124 which is fixed beneath the feed-table. A second arm 126, depending from the sleeve 122, is connected, by a rod 128, with an arm 130 (Fig. 2) which extends upwardly from a sleeve 131. The sleeve 131

is journaled on a rod 132 fixed in the column 24, and is provided with a depending arm 134 which carries a roller 136 in engagement with a cam 138 on the cam-shaft 34. 5 The cam mechanism acts, through the connections above described, to swing the stop-fingers 108 away from each other, and out of engagement with the endmost lift of the stack, at the time when this lift is to be 10 withdrawn by the picker-mechanism, while the opposite return movement of the parts is produced by a spring 139 attached to the arm 134.

The inclined position of the stud 110 has 15 the useful result that it causes the stop-fingers, in their movements into and out of operative position, to follow paths in planes inclined to the surface of the lift engaged by the fingers and remote from the edge of 20 this lift, so that the movement of the fingers cannot be interfered with by accidental engagement with the edge of the lift when the fingers return to operative position. This construction and mode of operation 25 constitute a novel feature of the present invention.

The feed-mechanism of the present machine is provided, like that of Letters Patent No. 1,280,349, with means for clamping 30 the lifts at the inner ends of the stack, to support them against the pressure of the picker-mechanism. These means comprise clamp-blocks 140 (Figs. 6 and 8) which are adjustably mounted on slides 142. The 35 slides have bifurcated upper ends, which are guided by a transverse guide-bar 144 fixed above the feed-table. At their lower ends, the slides are perforated and threaded to receive a shaft 146 having right and left hand 40 threads. The shaft 146 is journaled on the feed-table and is provided, at one end, with a pinion 148 meshing with a segmental gear 150 which is pivotally mounted on the feed-table. The gear 150 is fixed to a second 45 segmental gear 152, which is engaged by a rack 154 which slides vertically in a bearing on the side of the feed-table.

The rack 154 meshes, at its lower end, with a segmental gear 156 mounted on the 50 shaft 62. The gear 156 is yoke-shaped, and is journaled loosely on the shaft, but one of its lateral members is embraced between the fixed collar 68, and a second collar 157 (Fig. 7) which latter is also fixed to the shaft. 55 By means of coöoperating shoulders 160 on the gear and on the collar 68, the rotative movement of the gear on the shaft 62 is limited. A torsion-spring 158, interposed between the gear and the collar 157, and secured 60 at one end to the gear, and at the other end to the shaft 62, normally maintains the shoulders 160 in engagement, so that the rotation of the shaft 62 in one direction moves the gear positively, while 65 opposite rotation of the shaft moves the

gear yieldingly through the force of the spring 158.

The above described arrangement is such that rotation of the shaft 62, as yieldingly transmitted to the gear by the spring 158, causes a downward movement of the rack 154 which, in turn, through the gear-segments 150 and 152 and the pinion 148, causes rotation of the screw-shaft 146 in a direction to move the slides 142 and the clamp-blocks 75 toward each other and into firm engagement with the heel-lifts, while the opposite movement of the blocks, by which the heel-lifts are unclamped, is caused positively by the 80 opposite rotation of the shaft 62. The rotary movements are imparted to the shaft 62 by means which will be hereinafter described.

Since the clamps have only a short range of operative movement, it is necessary to 85 adjust them, in their original positions, according to the size of the heel-lifts upon which the machine is operating. For this purpose the pinion 148 is connected with the shaft 146 by means of a sleeve 162, which is 90 integral with the pinion and is splined upon the shaft. The sleeve is provided with a knurled head 164, and a compression-spring 168 is interposed between the sleeve and a disk 166 fixed on the end of the shaft, as 95 shown in dotted lines in Fig. 6. When adjustment of the clamps is required, the knurled head 164 may be pulled outwardly, thus sliding the pinion out of engagement with the gear-segment 150, and the head 100 may then be rotated in one direction or the other to move the clamps toward or from each other prior to the engagement of the pinion by the gear.

The picker-mechanism is shown particularly in Figs. 3, 8, 9, 10 and 11. A member 170 of the frame of the machine supports the bearing of a horizontal shaft 172, upon the inner end of which is mounted a rotatable multi-picker member comprising 110 four radial arms 174. Each of these arms constitutes a tubular guide-way in which one of the pickers is supported and guided.

Each picker has a shank mounted in one of the guide-ways 174, this shank comprising 115 a central rod or stem 176, on the inner end of which is fixed a collar 178 which fits and slides within the guide-way. Near the outer end of the shank, a sleeve 180 is fixed upon the stem, and is provided with 120 elongated gear-teeth 182 which also fit and slide within the guide-way. At the outer extremity of the shank is a head in which are secured four curved claws 184. These claws project helically from the head, that 125 is, in such a direction that they may be introduced into a heel-lift by a helical movement like that of a cork-screw. Each claw consists of a piece of wire bent into helical form and sharpened at one end. The head 130

in which the claws are fixed comprises an inner cylindrical member 186, which is integral with the stem 176 and is split to permit a slight resilient expansive movement.

- 5 The claws are seated in helical grooves in the member 186, and are closely embraced by a collar 188. A screw 190, threaded into the end of the stem, is provided with a conical head engaging a corresponding conical 70
10 perforation in the member 186, and when this screw is driven home, it expands that member so as to cause the claws to be securely clamped against the inner surface of the collar 188. Upon loosening the screw, 15 the collar may be removed, and the claws may then be readily removed for replacement or sharpening.

For the purpose of imparting longitudinal movements to the picker, a sleeve 192 is 20 mounted on the stem 176, and a compression spring 194 is interposed between the sleeve 180 and a washer 196 which is splined to the stem and rests against the sleeve 192. This spring acts to retain the sleeve 192 25 normally against the collar 178, as shown in Fig. 9. The sleeve has a lateral projection which extends through a longitudinal slot in the guideway 174, and carries a roller 198. This roller traverses a circular pathway 200 which is formed on the face of a 30 stationary disk 202. The disk is provided with a hub 204 which serves as a bearing sleeve for the shaft 172 and which is fixed in the frame member 170.

35 The engagement of the roller with the pathway retains the roller normally in its innermost position, as in Fig. 9, but, for the purpose of producing the outward movements of the roller by which the picker is 40 advanced, the pathway is interrupted at two points by gaps to permit the engagement of the roller with two actuating levers. One of these levers, 206, is provided with two lugs 208 which normally form a continuation of the pathway 200, as shown by dotted lines in Fig. 8. This lever 206 is pivoted on a stud 209, and its lower end is connected, by a rod 210, with an arm 212 projecting upwardly from a sleeve 214 which 45 turns on the rod 132, as shown in Fig. 2. Depending from the sleeve 214 is an arm 216 which carries a roller 218 engaging a cam 220 on the cam-shaft 34. The cam mechanism just described is so timed that when 50 one of the rollers 198 is moved into the space between the lugs 208 and has come to rest with the parts in the position of Fig. 8, the upper end of the lever 206 is swung toward the left, thus advancing the picker 55 into engagement with the exposed surface of the endmost lift in the stack on the feed table.

At the same time, it is necessary to advance the picker which is in the lowermost 60 position, this picker being that which has

received a lift from the feed table and which is in position to deposit the lift in one of the receptacles 33 on the intermittently rotatable carrier 31. For the purpose of advancing this lowermost picker, a second actuating lever 222 (Fig. 8) is employed, this lever being mounted upon a stud 224 and having lugs similar to the lugs 208 which enter a gap in the lower part of the pathway 200 and form a continuation thereof. 75

This lever 222 is actuated by connection with the lever 206. For this purpose, it is provided with an arm 226 which is connected, by a link 228, with the upper arm of the lever 206. 80

In order to lock the picker supporting arms 174 securely against any rotative movement during the advancing and retracting movements of the pickers, each arm is provided with two flanges 230 (Figs. 8, 9, and 11), which are located on opposite sides of the slots through which the rollers 198 move and are shaped to conform to the paths of movement of the lugs 208 on the levers 206 and 222 and to embrace said lugs when said 90 levers are actuated.

The rotative movements are imparted to each picker by a rack 232 (Figs. 9 and 10), which is mounted to slide in a transverse bearing on the corresponding arm 174. The 95 rack meshes with the teeth 182 on the shank of the picker. The movements of the rack are derived from the levers 206 and 222. For this purpose, a bell-crank lever 234 (Figs. 8, 9 and 10) is mounted on a stud 236 100 on the arm 174, and is connected, by a pivot 238, with one end of a slidable plate 240, which rests against the outer surface of the rack and retains it in its bearing. The other end of the plate 240 is connected, by 105 a stud 242, with a second bell-crank lever 244 which is mounted on a stud 246 on the arm 174. The rack is longitudinally bored to receive a tension spring 248, of which one end is fixed to a pin 250 in the rack, while 110 the other end is attached, by a pin 252, to the bell-crank lever 244.

In Fig. 8 the rack corresponding to that picker which is about to receive a heel lift is in its upper position, where it is retained 115 by the friction of the parts. After the picker has been longitudinally advanced, as above described, into engagement with a lift, the continued movement of the lever 206 results in a longitudinal sliding movement of the sleeve 192 on the stem 176, and in the yielding compression of the spring 194. At the same time, a lug 254 on upper 120 end of the lever engages the upper arm of the bell-crank lever 234 and rocks this lever in a direction to move the plate 240 downwardly. Owing to the tension of the spring 248 the rack 232 yieldingly participates in the downward movement, causing the picker to rotate so that the claws 184 125

65 130

which are yieldingly pressed against the lift by the spring 194 are introduced into the substance of the lift in a direction in extension of their curvature by a concurrent, 5 rotating and advancing movement. The claws 184 penetrate a greater or less distance into the lifts, according to the character of the material of which the lifts are composed. If the material of the lifts is hard, 10 the rotation of the claws may be arrested before their entire length has been inserted into the stock, but if the stock is sufficiently soft and yielding, the rotation may continue until the head of the picker has 15 been advanced into firm engagement with the surface of the lift by the force of the spring 194. The continued downward movement of the plate 240 after the rotation of the claws has been arrested is permitted by 20 elongation of the spring 248.

The contrary rotation of the picker, to release the lift, when the picker occupies its discharging position, is produced by engagement of the corresponding bell-crank lever 25 244 by a lug 256 on the lever 222. The lever 244 has an arm which engages the end of the rack and thus moves it positively to its original position.

For convenience in disassembling the 30 picker mechanism, for the purpose of replacing or sharpening the claws, or for other repairs, the plate 240 is arranged to be easily disengaged from the lever 244. The stud 242 (Figs. 8 and 10) is provided with a 35 flange 258 which is engaged by a plate 260, said plate being laterally slotted to receive the shank of the stud, as shown in dotted lines in Fig. 8. The plate 260 is mounted to swing about a pivot screw 262 and is provided, on its inner surface, with a boss 264 40 which normally is held in engagement with a recess in the plate 240 by the action of a spring 261 bearing against the plate 260. When the mechanism is to be disassembled, 45 the plate 260 may be swung out of engagement with the stud 242, whereupon this stud may be withdrawn from the lever 244. The plate 240 may then be swung out of engagement with the rack, which may then be 50 removed from its bearing and the picker can then be withdrawn from the arm 174.

Intermittent quarter-rotations are imparted to the shaft 172 by mechanism shown in part in Figs. 2 and 3. A skew-gear 266, 55 on the outer end of the shaft 172, meshes with a skew-gear 268 on the upper end of a shaft 270 which is journaled on the frame of the machine. The lower end of the shaft 270 is connected to any suitable means (not 60 shown) for intermittently rotating said shaft in such manner as to produce periodic quarter rotations of the shaft 172 and the associated multi-arm picker mechanism.

The means just referred to, for intermittently rotating the shaft 270 may conven-

iently comprise a mechanism similar to that shown and described in the hereinbefore mentioned Letters Patent No. 1,280,349, of which this application is a division, which mechanism may also serve to effect the intermittent longitudinal movements of the shaft 62 by means of which the feed chains 70 38 are actuated. These actuating mechanisms, however, form no part of my present invention, except as they perform certain 75 functions which are necessary to the operation of those parts which constitute the present invention. Therefore, no illustration and description thereof is deemed necessary.

The heel lifts are discharged by the picker mechanism into the series of receptacles 33 formed at the periphery of the circular carrier 31 which rotates about the vertical sleeve 29. At the periphery of the carrier 31 are 80 fixed a series of plates 308, which constitute supports upon which the lifts may rest in horizontal position. The lift receptacles are completed by abutments, in the form of fingers, arranged in pairs 310 and 312, which are adapted to engage the edges of the heel lift resting upon the support. The fingers 310 engage the curved rear edge of the heel lift, while the fingers 312 engage the breast edge. These fingers are adjustably fixed in 85 place, in accordance with the size of the lifts upon which the machine is operating.

The fingers are so adjusted as to closely confine the heel lift against lateral or 90 rotative movement in the plane of its extension, and accordingly, when the lift is introduced into one of the receptacles by the downward advancing movement of the lowermost picker, as before described, the subsequent 95 reverse rotation of the picker causes disengagement of the claws with the lift, since the fingers prevent this rotation from being shared by the lift. Upon the succeeding retraction of the picker, the lift is therefore 100 left lying in the receptacle.

As the operation of the machine proceeds, the multiple picker mechanism transfers the successive lifts from the stack upon the feed-table and deposits them into the successive receptacles upon the intermittently 105 rotatable carrier 31, that serves to transfer the lifts to the operative instrumentalities by means of which the lifts are gaged and subsequently distributed into suitable receptacles.

While the several features of the present invention have been illustrated and described as employed in conjunction, and in a machine for performing a particular operation upon heel lifts, it will be understood 115 that the several novel features are not limited to such conjoint and particular employment, but that the invention may be embodied in various other forms within the 120 scope of the following claims.

That which is claimed as new, is:—

1. In a stock-handling machine, feed-mechanism having, in combination, a horizontal support on which a stack of heel-lifts of heel-stock may rest with their curved surfaces downward, means for advancing the stack on the support; means for engaging and clamping the pieces laterally at one end of the stack; and a gage arranged to engage 5 and aline the breast-edges of the lifts which are in coöperative relation with the clamping-means.

2. In a stock-handling machine, feed-mechanism having, in combination, a support 15 on which a horizontal stack of pieces of stock may be supported; a gage for engaging and alining the upper edges of the pieces in the stack; and mechanism for moving the support and the gage simultaneously 20 and proportionately toward or from each other to adjust them to pieces of different sizes.

3. In a stock-handling machine, stock-holding means having, in combination, a plurality of horizontal members arranged to hold a stack of pieces of stock resting on their edges and to confine them laterally in all directions by engagement with various points on their edges; means for feeding the 25 stack of pieces in the direction of its length; and mechanism for moving all of said members simultaneously and proportionately toward or from each other to adjust them to pieces of different sizes.

35 4. In a stock-handling machine, a feed-mechanism having, in combination, means for supporting a horizontal stack of heel-lifts with their breast-edges upward; means for engaging and alining the opposite sides thereof; means for feeding said stack by engagement with the sides thereof; means disposed at one end of the stack for engaging and alining the breast-edges of the lifts; and means for concurrently adjusting the 40 supporting means and the side and breast-edge alining means.

5. In a stock-handling machine, a feed-mechanism having, in combination, a support upon which a horizontal stack of pieces 50 of stock may rest; means for engaging and alining the side and top edges of said pieces; means for advancing the stack; and means for concurrently adjusting the side and top alining means to accommodate pieces of different sizes.

6. A feed-mechanism for pieces of stock having, in combination, means for supporting and advancing a stack of pieces, and means disposed at the end of the stack movable into and out of engagement with the 55 exposed face of the end piece in the stack in a lateral direction in a plane that is inclined to the face thereof.

7. A feed-mechanism for pieces of stock 60 having, in combination, means for support-

ing and advancing a stack of pieces; and a stop-finger movable into engagement with the exposed face of the end piece in the stack, said finger being mounted upon a pivot inclined to the plane of the stack 70 whereby said finger moves in a plane inclined to the exposed face of said end piece.

8. A feed-mechanism for pieces of stock having, in combination, means for supporting and advancing a stack of pieces, means 75 disposed at the end of the stack movable into and out of engagement with the exposed face of the end piece in the stack in planes that are inclined to the face thereof, and means for actuating said means yielding 80 into engagement and positively out of engagement with said end piece.

9. A stock-handling machine having, in combination, a support for a stack of pieces of stock; means for removing pieces singly 85 from the end of the stack; a finger for engaging and retaining the endmost piece in the stack between successive operations of said means; and mechanism for moving the finger into and out of operative position in 90 a lateral direction along a path inclined to the surface of the endmost piece of stock.

10. A stock-handling machine having, in combination, means for holding a stack of pieces of stock; a rotatable device comprising 95 a plurality of pickers for successively seizing the endmost pieces in the stack; means for intermittently rotating said device to successively bring the several pickers into operative position; and means for positively locking said device in said operative 100 positions.

11. A stock-handling machine having, in combination, means for holding a stack of pieces of stock; a rotatable device comprising 105 a plurality of pickers for successively seizing the endmost pieces in the stack; means for intermittently rotating said device to successively bring the several pickers into operative position; and means for positively locking said device in said operative 110 positions and for advancing the operatively positioned picker into seizing relation with the endmost piece of the stack.

12. A stock-handling machine having, in combination, means for holding a stack of pieces of stock; a device rotatable about an axis substantially in line with the stack and comprising a plurality of radially disposed pickers; means for intermittently rotating said device to successively bring the pickers into operative position in alinement with the stack; and means for causing each operatively positioned picker to seize the endmost piece in the stack. 115

13. A stock-handling machine having, in combination, means for holding the stock; picker-mechanism comprising a plurality of concentric helically projecting claws; and means for engaging the claws with and ro- 120 125 130

tatively introducing them into the stock in said holding means.

14. In a stock-handling machine, picker-mechanism having, in combination, a claw 5 of helical form; a head comprising inner and outer concentric members between which the claw is clamped; and means for rotating the head.

15. In a stock-handling machine, picker-mechanism having, in combination, a claw 10 of helical form; an adjustable expansive member fitting within the claw; and a collar fitting outside the claw, the claw being clamped between said member and collar by 15 the expansion of the former.

16. In a stock-handling machine, picker-mechanism having, in combination, a shank provided with gear-teeth; a helical claw fixed at the end of the shank; a tubular 20 guideway for the shank; means for moving the shank longitudinally in the guideway; and means comprising a rack engaging said gear-teeth for rotating the shank in the guideway.

25 17. In a stock-handling machine, picker-mechanism having, in combination, a guide and supporting sleeve; a movable head disposed therein; a curved claw held by said head; means for yieldingly moving said head longitudinally in said sleeve; and means for yieldingly rotating said head in said sleeve to introduce said claw into the stock.

35 18. In a stock-handling machine, picker-mechanism having, in combination, a tubular guideway provided with a longitudinal slot and with a transverse bearing for a rack; a rack in said transverse bearing; a shank mounted in the guideway and provided with gear-teeth engaging the rack; a 40 lateral projection, from the shank, extending outwardly through said slot in the guideway; mechanism for engaging and moving said projection to advance the shank 45 in the guideway and for moving the rack to rotate the shank; and a helical claw mounted at the end of the shank.

50 19. In a stock-handling machine, picker-mechanism having, in combination, a tubular guideway; a shank mounted in the guideway; a helical claw mounted at the end of the shank; means for moving the shank longitudinally in the guideway, to engage the claw with a piece of stock, and 55 for rotating the shank to introduce the claw into the stock; and means for moving the guideway to transfer the stock from a position of reception to a position of discharge.

60 20. A stock-handling machine having, in combination, a stock-support, on which a piece of flat stock may lie, provided with abutments to engage the periphery of the piece of stock and prevent rotation thereof; a picker provided with a helically projecting claw adapted to enter and hold a piece 65

of stock; and means for moving the picker from a position of reception to a position in which the stock held thereby is applied to said support and introduced between said abutments thereon, and for thereafter rotating the picker to disengage the claw 70 from the stock.

21. A stock-handling machine, having, in combination, a curved claw; a head for holding said claw; teeth upon said head; a 75 rack co-operating with said teeth; and resilient means for actuating said rack to yieldingly rotate said claw into the stock.

22. In a stock-handling machine, feed mechanism having, in combination, means for supporting a stack of heel-lifts with their curved edges downward, means for advancing the stack on the support, means for engaging the opposite curved edges of a plurality of lifts adjacent one end of the stack 80 to clamp said lifts laterally, and a gage plate for alining the breast edges of the lifts engaged by said clamping means and preventing their upward displacement under 85 the influence of said clamping means. 90

23. In a stock-handling machine, picker-mechanism having, in combination, a head rotatable about an axis normal to the stock; a helically curved claw projecting therefrom; and means for advancing the head and claw in an axial direction and concurrently rotating the head and claw to cause the claw to penetrate the stock with a combined advancing and rotative movement in a direction in extension of its curvature. 100

24. In a stock-handling machine, picker-mechanism having, in combination, a rotatable head; a helically curved claw projecting therefrom; and means for advancing the head and claw in a direction normal to the 105 stock to cause the claw to engage the stock and subsequent to the engagement to continue the advancing movement and concurrently rotate the claw to cause it to penetrate the stock with a combined advancing and rotative movement in a direction in extension of its curvature. 110

25. In a stock-handling machine, picker-mechanism having, in combination, a head 115 rotatable about an axis normal to the stock; a helically curved claw projecting therefrom; means for advancing the head and claw in an axial direction to engage the claw with the stock; and co-operating means for causing the claw to yieldingly penetrate the stock with a concurrent advancing and rotative movement in a direction in extension of its curvature. 120

26. A stock-handling machine having, in combination, means for holding and preventing angular displacement of the stock; and a picker-mechanism for seizing and transferring the stock comprising a helically curved claw rotatable about an axis 125 normal to the stock; and means for intro- 130

ducing the claw into firm seizing relation with the stock in said holding means by a concurrent advancing and rotative penetratin movement in a direction in extension of its curvature.

- 5 27. A stock-handling machine having, in combination, means for holding the stock against displacement; picker-mechanism having a helically curved claw rotatable about an axis normal to the stock, means for 10 rotating the claw and concurrently advancing it in an axial direction to cause it to

penetrate and seize the stock in said holding means; a support provided with abutments to receive the stock from said picker-mechanism and retain it in definite position; means for causing said picker-mechanism to transfer the stock and position it upon said support and between said abutments; and means for rotatably releasing said claw from 15 the stock definitely positioned upon said support.

ERASTUS E. WINKLEY.
